UNITED STATES PATENT OFFICE.

NILS M. ROSENDALH, OF WINTHROP HARBOR, ILLINOIS, ASSIGNOR TO FREDERICK C. AUSTIN, OF CHICAGO, ILLINOIS.

ROTARY DRIER.

1,229,524.

Specification of Letters Patent. Patented June 12, 1917.

Application filed November 5, 1914. Serial No. 870,444.

To all whom it may concern:

Be it known that I, NILS M. ROSENDALH, a citizen of the United States of America, and resident of Winthrop Harbor, Lake 5 county, Illinois, residence address corner Whitney avenue and North Park avenue, have invented a certain new and useful Improvement in Rotary Driers, of which the following is a specification.

10 My invention relates to rotary driers for use in machines for drying crushed rock, sand, gravel or other similar materials preparatory to combining the same with asphalt or other material. Generally stated, the object 15 of my invention is to provide a novel and highly efficient rotary drier of the foregoing general character. Special objects are to provide a novel construction and arrangement whereby the length of the rotary drum 20 is reduced to a considerable extent without shortening or reducing the efficiency of the drying operation; to provide an improved construction and arrangement whereby the vapor and dust are drawn out of the drum 25 by a current of air produced by a suction blower or similar draft producing means; and to provide certain details and features of construction and combinations tending to increase the general efficiency and service- 30 ability of a rotary drier of this particular character.

To these and other useful ends my invention consists in matters hereinafter set forth and claimed.

35 In the accompanying drawings—

Figure 1 is a longitudinal section of a rotary drier embodying the principles of my invention.

Fig. 2 is a cross section on line 2—2 in 40 Fig. 1.

Fig. 3 is a vertical transverse section on line 3—3 in Fig. 1.

Fig. 4 is a rear end elevation of the drier shown in Fig. 1.

45 Fig. 5 is a vertical transverse section on line 5—5 in Fig. 1.

As thus illustrated, my invention comprises a drum A arranged to rotate about a horizontally disposed axis. Said drum is 50 provided with a removable head B at its rear end, and with a removable head C at its forward end, the latter head or casting having an opening c which forms the inlet for the materials. This head C is also provided with air inlet openings c¹, and similar

openings b are provided in the head B, the latter being also provided with outlets b¹ for the materials, said outlet openings being arranged in a circle at the extreme outer edges of the said head. In addition the 60 head B is provided with a central trunnion b² that rests upon the rollers b³ of the bearing support b⁴, whereby the rear end of the drum is supported by an idler bearing for 65 rotation, whereby there is no transmission of power through the outer drum. The head C is provided with a similar trunnion c² which rests upon the rollers c³ of the supporting bearing c⁴, whereby the forward 70 end of the drum is also supported for rotation. For this purpose, the trunnion c² is provided with a sprocket wheel c⁵ which is connected by a sprocket chain c⁶ with the sprocket c⁷ on the driving shaft c⁸ disposed 75 a distance below. The casting D is hollow and provided with a cylinder d which extends and fits within the trunnion c², being long enough to project a distance into the opening c or inlet of the drum. Said cylinder d is provided interiorly thereof with a 80 smaller concentric cylinder d¹, whereby a space d² is provided between these two cylinders, which space communicates with the air outlet or suction pipe d³ leading from the side of the casting. The space d², it will 85 be seen, communicates with the interior of the drum, whereby air is drawn through the drum during its rotation, the said current of air entering through the openings c¹, b and b¹ in the manner indicated by the arrows. 90 A spider bearing d⁴ is secured to the inner end of the cylinder d, which latter extends through a bearing d⁶ at the outer side of the casting. A sprocket d⁷ is secured to the outer end of this shaft, a sprocket d⁸ is secured to the shaft c⁸, and a sprocket chain d⁹ connects these sprockets together, whereby the rotation of the shaft c⁸, by any suitable means, causes the shaft d⁶ and drum A to rotate. A spiral flange or screw feed d¹⁰ 100 is secured to the shaft d⁶, in the cylindrical feed chamber d¹¹, and the outer end of this chamber is provided with a feed hopper d¹² to which the materials are delivered by any suitable means. The arrangement is such 105 that when the machine is in operation the said materials are fed through the chamber d¹¹ by the spiral flange or screw feed d¹⁰ and into the forward end of the drum. Thus the materials are forcibly fed 110.

into the drum, and at the same time an outgoing current of air is maintained through the feed opening of the drum, whereby dust and moisture are withdrawn 5 from the drum through the same opening through which the materials are fed into the drum. The interior of the said drum is provided with means or instrumentalities for causing the materials to travel back and forth from one end of the drum to the other. The said instrumentalities include an inside cylinder E which has its forward end secured to the head or casting C and thus arranged in position to receive materials. This 10 cylinder is provided internally with blades e which are set at an angle to propel the materials toward the rear end of the drum when the latter is rotated. A second cylinder F has its rear end secured to the head or casting B, this cylinder being arranged outside of the cylinder E, and the two cylinders and the drum being concentrically arranged relative to each other. The cylinder F is provided with blades f which are 15 set at an angle opposite to the angle of the blades e, whereby the materials escaping from the rear end of the cylinder E are then caused to travel in the opposite direction by the blades f in the cylinder F, it being observed that this is in a direction opposite to 20 the direction of travel of the air. The interior of the drum A is provided with similar blades a, these blades being set at the same angles as those of the blades e, whereby 25 the materials discharged from the front end of the cylinder F are then carried in the opposite direction by the blades a and caused to discharge from the drum through the openings b¹ at the other end thereof. Thus 30 the materials are caused to travel away from the axis of the drum in a zigzag manner, so to speak, inasmuch as the direction of travel is not only gradually away from said axis, but is also parallel with said axis to a large 35 extent. The general effect, therefore, so far as the drying of the materials is concerned, is practically the same as though the materials had been conducted through a rotary drum of substantially three times the length 40 of the one shown and described; for by the time the materials have progressed from the feed opening to the discharge openings b¹ of the drum, a distance has been traversed which is only a little less than three times 45 the length of the drum, in view of the fact that the materials have first traveled from one end to the other of the cylinder E, and then from one end to the other of the cylinder F, and finally from one end to the other 50 of the said drum.

In practice, the said drum is inclosed by a suitable housing G, which housing is provided with a discharge spout g which receives the materials from the outlet openings b¹ of the drum. Any suitable means

can be employed below the drum for heating the same, and within said housing, whereby the materials are heated while being tumbled about within the rotary drum. Also, it will be seen that by employing some sort of heating means below the drum, in the manner explained, the heated air and products of combustion are drawn directly into the air by the suction apparatus previously described, thus causing all moisture to be 75 carried out of the drum in the manner previously explained. With a rotary drier of the foregoing character the materials are thoroughly dried, and in addition the dust is thoroughly extracted, whereby the materials 80 are both dry and clean when finally discharged from the said spout.

The end walls g of the housing are disposed between the bearings c⁴ and b⁴ and the ends of the drum. With this arrangement 85 the heated air and products of combustion within the housing must enter the openings c¹ and b and b¹, but the bearings are outside and are not heated. Also, the bearing c⁴ is between the sprocket c⁵ and the end of 90 the drum, and is thus outside of the housing and in position to receive power from the drive shaft c⁸ below. Thus the trunnion c² forms the inlet of the drum for the materials, fits tightly around the fixed cylinder 95 to exclude the air, and serves as means for rotating the drum. The trunnion b² forms the closed end of the drum at the axis thereof.

This application covers an improvement 100 on the drier shown and described and claimed in my prior application Serial No. 829,748, filed April 6, 1914.

What I claim as my invention is:—

1. A rotary drier comprising a horizontally disposed drum, bearings for supporting said drum for rotation about a longitudinal axis, said drum having an axial inlet and peripheral outlet openings for the materials, instrumentalities within said drum for causing the materials to travel back and forth from one end of the drum to the other during the rotation thereof, a trunnion rigid with one end of said drum to support the latter on one of said bearings and forming an intake, for the inlet opening, a device externally engaging said trunnion to rotate said drum, and rotary means engaging the other bearing to support and axially close the rear end of said drum, 110 said instrumentalities including concentric cylinders attached respectively to opposite ends of said drum, causing the materials to travel away from said axis, a housing for inclosing said drum, said housing having 115 end walls disposed between said bearings and the ends of said drum, the other end of each cylinder being unsupported.

2. A rotary drier comprising a horizontally disposed drum, bearings for support- 120

ing said drum for rotation about a longitudinal axis, said drum having an axial inlet and peripheral outlet openings for the materials, instrumentalities within said drum for causing the materials to travel back and forth from one end of the drum to the other during the rotation thereof, a trunnion rigid with one end of said drum to support the latter on one of said bearings and forming an intake, for the inlet opening, a device externally engaging said trunnion to rotate said drum, and rotary means engaging the other bearing to support and axially close the rear end of said drum, said instrumentalities including concentric cylinders attached respectively to opposite ends of said drum, causing the materials to travel away from said axis, a drive shaft below said trunnion, a connection between said device and said shaft, one of said bearings being disposed between said device and the end of said drum, the other end of each cylinder being unsupported.

3. A rotary drier comprising oppositely arranged rotary heads, a cylindric imperforate drum arranged horizontally and having its ends secured to said heads, concentrically arranged imperforate cylinders in said drum, secured endwise to said heads, devices to rotate one of said heads, a plurality of longitudinal rows of feed plates secured to the inner surface of said drum, similar rows of feed plates secured to the inner surface of each cylinder, said plates being disposed at angles oblique to the length of each row, with spaces between adjacent rows, thereby to feed the materials back and forth in the direction of said rows, means to deliver the materials through said devices to one end of the inner cylinder, one head having outlets for the materials, and a suction connection associated with said means to draw air through said drum and cylinders.

4. A rotary drier comprising oppositely arranged rotary heads, a cylindric imperforate drum arranged horizontally and having its ends secured to said heads, concentrically arranged imperforate cylinders in said drum, secured endwise to said heads, devices to rotate one of said heads, a plurality of longitudinal rows of feed plates secured to the inner surface of said drum, similar rows of feed plates secured to the inner surface of each cylinder, said plates being disposed at angles oblique to the length of each row, with spaces between adjacent rows, thereby to feed the materials back and forth in the direction of said rows, means to deliver the materials to one end of the inner cylinder, one head having outlets for the materials, and a suction connection associated with said means to draw air through said devices from said drum and cylinders, said heads being each secured to one of said cylinders, so that each cylinder is supported only at one end

thereof, and whereby the cylinders can be untelescoped by merely disconnecting said heads from the drum.

5. A rotary drier comprising oppositely arranged rotary heads, a cylindric imperforate drum arranged horizontally and having its ends secured to said heads, concentrically arranged imperforate cylinders in said drum, secured endwise to said heads, devices to rotate one of said heads, a plurality of longitudinal rows of feed plates secured to the inner surface of said drum, similar rows of feed plates secured to the inner surface of each cylinder, said plates being disposed at angles oblique to the length of each row, with spaces between adjacent rows, thereby to feed the materials back and forth in the direction of said rows, means to deliver the materials to one end of the inner cylinder, one head having outlets for the materials, and a suction connection associated with said means to draw air through said drum and cylinders, said outlets and means being at opposite ends of the drum, and each cylinder being shorter than said drum.

6. A machine for preparing materials, comprising a plurality of hollow members arranged one within the other, having imperforate sides, means for rotating said members about a common axis, apparatus for sucking the dust and moisture laden air through said means from said members, means at one end of the machine for feeding the materials to the innermost member, an idler bearing for said member at the other end of said machine, means within the members for feeding the materials back and forth therein, from one member to the other by the rotation of said members in unison, and means for receiving the materials from the outermost member.

7. A machine for preparing materials, comprising a plurality of hollow members arranged one within the other, having imperforate sides, mechanism for rotating said members about a common axis, means at one end of the machine for feeding the materials to the innermost member, an idler bearing for said member at the other end of said machine, means within the members for feeding the materials back and forth therein, from one member to the other, means for receiving the materials from the outermost member, said first-mentioned feeding means extending through said mechanism, means connected with said mechanism to drive said first-mentioned feeding means, and a suction-connection to draw the air through said mechanism from said members, so that the dust and moisture from the materials are sucked out through said mechanism during the operation thereof.

8. A machine for preparing materials, comprising a plurality of hollow members arranged one within the other, having im-

perforate sides, means for rotating said members about a common axis, means for feeding the materials to the innermost member, means within the members for feeding 5 the materials back and forth therein, from one member to the other, and means for receiving the materials from the outermost member, the outer member being cylindric and provided with supporting heads at opposite ends thereof, and said last-mentioned feeding means consisting of rows of oblique blades extending parallel with said axis.

9. A machine for preparing materials, comprising a plurality of hollow cylindric 15 members arranged concentrically one within the other, having imperforate sides, mechanism for rotating said members about a common axis, means at one end of the machine for feeding the materials through said 20 mechanism to the innermost member, an

idler bearing for said member at the other end of said machine, means within the members for feeding the materials back and forth therein, from one member to the other, by the rotation of said members in unison, 25 means for receiving the materials from the outermost member, means connected with said mechanism to drive said first-mentioned feeding means, the outermost member being supported at both ends thereof, and the inner members being each supported only at one end, the inner members being shorter than said outermost member.

Signed by me at Chicago, Cook county, Illinois, this 17th day of October, 1914.

NILS M. ROSENDAHL.
